UNITED STATES PATENT OFFICE

PAUL E. KLOPSTEG, OF CHICAGO, ILLINOIS, ASSIGNOR TO CENTRAL SCIENTIFIC COMPANY, OF CHICAGO, ILLINOIS, A CORPORATION OF ILLINOIS

CARBON RHEOSTAT

Application filed February 16, 1929. Serial No. 340,575.

This invention relates to carbon rheostats and has for its principal object to increase the stable range, the precision of adjustment and the ability to dissipate heat.

Further objects and advantages of the invention will become apparent as the disclosure proceeds and the description is read in connection with the accompanying drawings illustrating a preferred embodiment of the invention, and in which

Fig. 1 is a side elevation of a carbon rheostat having somewhat familiar characteristics but embodying this invention, the intermediate portion of the rheostat being broken away;

Fig. 2 is a vertical section taken on the line 2-2 of Fig. 1; and

Fig. 3 is a perspective view illustrating the manner of associating the carbon and metal plates.

But this specific illustration and the corresponding description are used for the purpose of disclosure only and are not intended to define the limits of the invention, for I realize that it may be embodied in other forms.

The frame of the rheostat comprises end castings 10 and 11 rigidly connected in spaced relation by rods 12, 13 and 14 equipped with nuts 15.

The trough is formed by two bars 16 and 17 of heat resisting insulating material such as asbestos slate, the ends of which are supported on inwardly directed inclined lugs 18 and 19 which support the bars 16 and 17 with their lower edges separated to leave the bottom of the trough open.

Arranged in the trough on edge with their diagonals horizontal and vertical are a series of square plates 20 of hard carbon. At the ends of the series are square plates 21 of metal equipped with terminals 22. Outside the plates 21 are heat resisting insulating plates 23, one of which bears against the inner side of the casting 11 and the other receives the thrust of a screw 24 equipped at its inner end with a pressure plate 25. The screw 24 is threaded in a boss 10a on the casting 10 and its outer end is fitted with a knob or hand wheel 26.

Interposed between adjacent carbon plates

20 are metal plates 27 substantially rectangular in shape, with one dimension equal to a side of the square plates 20. At one lower corner the plates 27 have rectangular projections 28 which extend through the bottom of the trough as best illustrated in Fig. 2.

The metal plates may be made of a variety of materials and in a variety of forms. Steel, nickel and phosphor-bronze from .003 to .005 of an inch thick have been found very satisfactory. They should have sufficient flexibility to yield readily under pressure of the screw 24 and should have sufficient resiliency to promptly expand the series of plates as the pressure of that screw is relieved. This characteristic is readily provided by curving the plates 27 on the arc of a large circle, as best illustrated in Figs. 1 and 3.

In using such plates they should be arranged in two series as best illustrated in Fig. 2, adjacent plates being in alternate series. As shown in the drawings, the convex faces of the resilient plates in one series all face in the same direction, while the convex faces of the other series face in the opposite direction. This will overcome the tendency of the column of plates to buckle and will afford better radiation.

The rheostat is used in the usual manner and adjustments are made by turning the screw 24. An old type carbon rheostat of familiar construction will give resistance up to six or eight ohms, but at their higher values the resistance varies greatly in different operations. Its action may be described as erratic. Such a rheostat, equipped with metal plates 27, will have a resistance up to forty or fifty ohms with fixed values at any setting of the screw within the range of the device. It will also dissipate heat two or three times as rapidly, and since the resistance of carbon decreases as the heat rises, even the heat radiation of the improved structure becomes an important advantage.

The heat generated by the current is rapidly conducted to those portions of the metal plates 27 that extend beyond the carbon plate, and by those portions to the air surrounding them, thus producing convective currents traversing radiating surfaces of great area.

In the form shown in the drawings, there are in effect four radiators of great area and high efficiency.

I claim as my invention:

- 6 1. In a carbon rheostat of the type including a number of carbon plates arranged side by side, and means for pressing the plates together with variable pressure, the combination of curved resilient metal plates interposed between adjacent carbon plates and arranged in two longitudinal series angularly disposed with respect to each other, and projecting laterally beyond the margins of the carbon plates.
- 10 2. In a carbon rheostat of the type including a number of carbon plates side by side in a trough and means to vary the pressure between the plates, the combination of curved resilient metallic plates interposed between adjacent carbon plates and arranged in two longitudinal series with the axes of curvature in the series at an angle.
- 15 3. In a carbon rheostat, a trough including two plates inclined oppositely from the vertical and spaced apart at their lower edges, a number of carbon plates side by side in the trough, resilient metal plates interposed between adjacent carbon plates and projecting through the bottom of the trough in alternate series angularly disposed with respect to each other, and means to vary the pressure on the plates.
- 20 4. In a carbon rheostat, a trough including two plates inclined oppositely from the vertical and spaced apart at their lower edges, a number of carbon plates side by side in the trough, resilient metal plates interposed between adjacent carbon plates and projecting through the bottom of the trough, said carbon and resilient plates being arranged in two longitudinal series at an angle with each other and having adjacent resilient plates in alternate series, and means to vary the pressure on the plates.
- 25 5. In a carbon rheostat of the type including a substantially open trough and a number of carbon plates arranged side by side therein, the combination of curved resilient metal plates interposed between the several carbon plates and arranged so that the convex faces of alternate resilient plates face in one direction while the other resilient plates have their convex faces facing in the opposite direction to prevent buckling of the combination of plates, and means for varying the pressure on the plates.

In testimony whereof I affix my signature.

PAUL E. KLOPSTEG.
